(57) **CLAIM**

The ornamental design for a solar panel cable tray, as shown and described.

DESCRIPTION

FIG. 1 is a bottom, perspective view of a solar panel cable tray;

FIG. 2 is front perspective view of the solar panel cable tray;

FIG. 3 is a back view of the solar panel cable tray;

FIG. 4 is a front view of the solar panel cable tray;

FIG. 5 is a bottom view of the solar panel cable tray;

FIG. 6 is a top view of the solar panel cable tray;

FIG. 7 is an end view of the solar panel cable tray; and,

FIG. 8 is an opposing end view of the solar panel cable tray.

The broken lines in the drawings depict portions of the solar panel cable tray that form no part of the claimed design.
